B. O. TILDEN

FLUSH VALVE OPERATING MECHANISM

Filed Nov. 12, 1924

UNITED STATES PATENT OFFICE.

BERT O. TILDEN, OF TRENTON, NEW JERSEY, ASSIGNOR TO B. O. T. MFG. CO., OF TRENTON, NEW JERSEY, A CORPORATION OF NEW JERSEY.

FLUSH-VALVE-OPERATING MECHANISM.

Application filed November 12, 1924. Serial No. 749,436.

To all whom it may concern:

Be it known that I, BERT O. TILDEN, a citizen of the United States, residing at Trenton, in the county of Mercer and State 5 of New Jersey, have invented certain new and useful Improvements in Flush-Valve-Operating Mechanism, of which the following is a specification.

This invention relates to improvements 10 in flush valve operating mechanisms, designed particularly for use in connection with vitrified china flush tanks, and has for its object to provide a novel and simple fitting of the class, wherein all of the exposed 15 parts are made of durable and ornamental vitreous material, which are arranged to effectually conceal all of the metal connecting and supporting parts. A further object is to provide novel and simple means for securing the china and other operating parts 20 in place, and for adjusting said means for facilitating the installing of said mechanism upon tanks of varying thickness and contour. And a further object is to generally 25 improve, simplify and render sanitary and ornamental flush tank fittings of the class.

This invention relates particularly to improvements in the devices shown and described in my United States Patent Number 30 1,061,705, dated May 13, 1913.

I attain these objects by the means set forth in the detailed description which follows, and as illustrated by the accompanying drawing, in which—

35 Figure 1 is a top end view of a flush tank with the cover removed. Fig. 2 is a broken front side elevation of the same. Fig. 3 is a broken end elevation of the tank. Fig. 4 is a horizontal section, taken centrally 40 through the operating parts shown in Fig. 1. Fig. 5 is respectively an end and a side view of the threaded sleeve in which the rock-shaft is journaled. Fig. 6 is respectively a front end, a rear end, and a side 45 view of the china knob or head. Fig. 7 is an enlarged edge view of the spanner-nut. And Fig. 8 is respectively a top, a bottom, and a central vertical cross-section of the 50 china escutcheon, the section being taken on line $x-x$ of the top end view.

In the drawing, 2 represents a china flush tank, which is supplied with the flushing

water by a pipe 3, the water being delivered to the tank through an elevated ball-cock 4, which is controlled by an ordinary float 55 5. The tank 2 is emptied during the flushing periods by means of a bottom outlet, which is controlled by the usual hollow rubber flush-valve 6, the said valve being lifted by a rod 6, to one end of which a rockable 60 operating lever 8, that forms a part of the present combination connects, as shown in Figs. 1 and 3. The opposite end portion of the lever 8 is formed substantially U-shape, as at 8', and adjacent the opposite 65 ends of the U, said lever passes through perforated ears or lugs 9' of a bracket 9, which is mounted on the inner front wall of the tank 2. The bracket 9 has a central opening 9^a, and a concentrically arranged 70 hub or sleeve portion 9^b, which extends into a molded opening 2' of the tank, as shown in Figs. 3 and 4. The bracket 9 is mounted on the inner end of an externally threaded 75 sleeve-bushing 10, the said end being fitted 80 with a nut 12, which engages the bracket for holding the parts in place. The sleeve 10 extends through, and beyond the outer face of, the tank, and near its outer end is fitted with a flange-bushing 13, the barrel of which 85 is disposed in the opening 2', while the flange bears against the outer face of the tank, as best seen in Fig. 4. The tightening up of the nut 12 and the bushing 13 rigidly 90 clamps the bracket 9 against the inner wall 95 of the tank. Beyond the bushing 13, a centrally perforated china escutcheon 14 is mounted on the sleeve 10, and is held in place with its flaring base 14' in close contact with the surface of the tank, by a spanner-nut 15, which engages the threaded outer 100 end of the sleeve (see Fig. 4). The relatively broad base 14' of the escutcheon is formed with a recess or cavity 14^a, and the annular face surrounding the cavity is also formed slightly concave, for facilitating the mounting of said part upon a convex or curved wall, the said concave being shown at 14^b in Fig. 4. The opposite or outer end of the escutcheon is formed with a concentric socket 14^c, which receives and is partially filled by the nut 15. The lever 8 is rocked for opening the valve 6, by a trip, which comprises a relatively large oval loop

16, through which the U-shaped portion 8' of the lever 8 loosely passes, and a stem 16', which passes through and is rotatable in the sleeve 10. The stem 16' extends beyond the outer end of the sleeve 10, and its free end is disposed in a socket 17' of a china knob or head 17, the latter being substantially spherical, and having its inner end or side seated in the socket 14' of the escutcheon in contact with the nut 15. The stem 16' is provided with a transverse threaded hole 16'', which registers with a corresponding opening 17'' of the head, through which a threaded stud 19' of a china operating handle 19 is inserted for operatively connecting and holding the parts together. The stud 19' is preferably rigidly embedded in the handle 19, and a washer 20 of cushion or fibrous material is preferably disposed between the end of the handle and the head, for preventing injury to the china parts when the latter are drawn tightly together. The washer 20 preferably nests in a shallow circular cavity 17'' of the head. The stem 16' of the trip is preferably a small fraction of an inch longer than the exact distance from the inner end of the sleeve 10 to the stud 19', to relieve binding and crunching of the china and other parts during the flushing operations.

It is a well-known fact that the walls of all china tanks vary in thickness and that the planes of the inner and outer surfaces of said walls are seldom exactly parallel to each other. In view of the prevalence of these variations, it is necessary to provide all fittings which are attached to and operate through the walls of the tanks, as for example, flush-valve operating mechanisms, as herein shown and described, with means for overcoming said variations. To this end, the escutcheon 14 is preferably loosely mounted on the sleeve or hollow post 10, and may therefore be tilted at different angles relatively to the axis of the sleeve, whereby its base 14' may come to a firm bearing against the outer face of the tank. And in order to properly secure the escutcheon in such self-adjusting positions, the bottom of the socket 14' is formed concave, as shown in Figs. 4 and 8, and the bottom or inner face of the spanner-nut 15, which engages the said socket, is formed convex, as at 15', for producing a universal or ball joint, by means of which the escutcheon may be adjusted and held in the desired position, even though the outer surface of the tank wall may not be parallel to its inner surface, as explained. In order to further insure the proper seating of the escutcheon against the tank, the threads of the nut 15 preferably loosely engage the threads of the sleeve 10. This allows the nut to cant sufficiently to relieve binding and straining of the parts.

65 My improved flush valve operating mech-

anism is extremely simple, and may be readily and quickly assembled, adjusted and installed upon any flush tank of the class shown, the construction and arrangement of the parts being such that the fitting may be conveniently and permanently applied to vitrified tanks having a single molded opening, as 2', which obviates all danger of marring the finish of the tanks, and besides greatly reduces the labor and cost of installing the fitting. The provision of the peculiarly shaped escutcheon and head, as well as the handle, all of which are constructed of china and vitrified like the tank, enables me to meet the popular demand for a durable pure white enameled toilet fixture, which is not only sanitary to the highest degree, but presents a pleasing ornamental effect, which is very desirable.

Having thus described my invention, what I claim, is—

1. The combination with a china flush tank having a molded opening, a flush valve in the tank, and a trip for operating said valve, said trip having a stem protruding through said opening, a china escutcheon through which said stem extends having an outwardly facing socket, means for clamping said escutcheon against the outer face of the tank, a china head receiving and concealing the free end of said stem and loosely engaging said socket, a handle depending from the head, and metal means carried by the handle and engaging the free end of said stem.

2. The combination with a china flush tank having a convex wall formed with a molded opening, a flush valve, a trip for operating said valve, said trip having a stem extending outwardly through the opening in said wall, a threaded tubular member extending through said opening in which said stem journals, means engaging the opposite sides of the wall for rigidly holding the said member in place, a china escutcheon mounted concentrically on said member and stem having a concave base conforming to the convex wall, said escutcheon having a recess, a china head mounted on the free end of said stem beyond the escutcheon and nesting in said recess, a gravitational china handle, and concealed metal means embedded in the handle adapted to operatively engage said stem.

3. A flush valve operating mechanism for china flush tank, including a trip adapted to open the valve, said trip having a stem extending outwardly through an opening in the wall of the tank, a threaded sleeve forming a bearing for said stem, a bracket supported by the inner end of said sleeve, a bushing threaded on said sleeve and engaging the outer face of the tank adapted for clamping the bracket tightly against the inner face of the tank, a china escutcheon mounted on said sleeve beyond said bushing,

- means engaging said sleeve for clamping the escutcheon against the outer face of the tank, a china knob mounted on the outer end of said stem concentric to the escutcheon, a china operating handle depending from said knob, and means for connecting said handle to the free end of said stem.
4. The combination with a china flush tank having a molded opening in one wall, 10 a flush valve, a lever for operating said valve, and a bracket for supporting said lever, of a threaded sleeve for supporting said bracket, a strip having a loop engaging said lever and having a stem that journals in said sleeve, the free end of said stem extending beyond the outer wall of the tank and beyond said sleeve, a head made of china enclosing the free end of said stem, a china escutcheon supported by and 20 sealing the outer end of said sleeve, means engaging the sleeve for clamping the escutcheon against the outer face of the tank, a handle depending from said head and operatively engaging the free end of said stem adapted to rock said trip in opposite directions, and means engaging said sleeve and concealed by said escutcheon for rigidly holding the sleeve and the bracket in place.
5. The combination with a china flush tank having an opening in one wall, a flush valve, and the lever for operating said valve of a bracket disposed in said tank adapted to pivotally support said lever, a trip comprising a loop engaging said lever and having a stem extending through the bracket and through and beyond the opening in the tank, a hollow threaded member disposed in said opening through which said stem passes, a china head mounted on said stem beyond the outer end of said member, a china escutcheon interposed between said head and the tank, means engaging said member for rigidly holding the escutcheon against the tank, means for rigidly clamping the bracket against the tank, a gravitational handle for rocking said head and said stem, and concealed metal means for detachably securing the handle to the free end of the stem.
6. The combination with a china flush tank, a flush valve, a lever for operating said valve, and a bracket pivotally supporting said lever, of a threaded sleeve passing through an opening in a wall of the tank and extending through said bracket, means engaging said sleeve at the opposite sides of said wall for rigidly clamping the bracket against said wall and for holding said sleeve at right angles to said wall, a plurality of china parts projecting beyond said wall, comprising an annular escutcheon mounted concentrically on the sleeve, and having a concave base that engages the convex outer face of the tank, 60 said escutcheon having a recess, a trip for operating said lever, said trip having a stem which passes through said sleeve, a head mounted concentrically on the free end of said stem beyond the sleeve, a portion of said head nesting in said recess, and a handle depending from said head and detachably engaging the free end of said stem adapted for rocking said trip and said lever for opening the flush valve.
7. The combination with a china flush tank having a molded opening in one wall, a flush valve, and a lever for opening said valve, of a threaded sleeve disposed in the opening of the tank, a bracket for supporting said lever mounted on the inner end of said sleeve, a nut for holding said bracket in place, a trip for operating said lever, said trip having a stem which passes axially through said sleeve and bracket, the free end of said stem extending beyond the outer end of the sleeve and having a threaded hole, a bushing mounted on said sleeve outside of the tank having a flange engaging the outer face of the tank, adapted when tightened up to rigidly clamp the bracket against the inner wall of the tank, a vitrified escutcheon mounted concentrically on the sleeve and concealing said bushing, said escutcheon having an outwardly facing recess, a spanner-nut disposed in said recess and threaded to the sleeve adapted to clamp the escutcheon against the outer wall of the tank, a vitrified head mounted on the outer end of said stem extending into said recess and engaging and concealing said nut, said head having an opening registering with the hole in the stem, and a vitrified handle engaging the free end of the stem adapted for rocking said head and said trip.
8. The combination with a china flush tank having a molded opening, a flush valve in the tank, and a trip for operating said valve, said trip having a stem protruding through said opening, a china escutcheon through which said stem extends having an outwardly facing concave socket, a nut having a convex face engaging said socket for adjustably clamping the escutcheon against a tank wall when the outer face of the tank wall is not parallel to its inner face, a china head receiving and concealing the free end of said stem and loosely engaging said nut, a handle depending from the head, and concealed metal means carried by the handle adapted to engage the free end of said stem.
9. A flush valve operating mechanism including a threaded sleeve adapted to be inserted through the wall of a flush tank, a trip for operating the flush valve having stem journaled in said sleeve, the free end of said stem extending beyond the outer end of the sleeve, a china escutcheon loosely mounted on said sleeve, said escutcheon having a concave socket adjacent the outer

end of the sleeve, a nut having a convex face engaging the concave of said socket adapted for clamping the escutcheon against the uneven or curved outer face of the tank, a hollow china head mounted upon and concealing the free end of said stem, a china handle, concealed metal means for detachably connecting the handle to the free end of said stem, and means for rigidly securing said sleeve to the wall of the tank.

In testimony whereof I affix my signature.

BERT O. TILDEN.
